UNITED STATES PATENT OFFICE.

HENRY F. POPE, OF CLEVELAND, OHIO, ASSIGNOR TO THE NATIONAL MALLEABLE CASTINGS COMPANY, OF CLEVELAND, OHIO, A CORPORATION OF OHIO.

PIVOT-PIN SUPPORT FOR COUPLINGS.

1,072,162.

Specification of Letters Patent. Patented Sept. 2, 1913.

Application filed January 18, 1907. Serial No. 352,880.

To all whom it may concern:

Be it known that I, HENRY F. POPE, a citizen of the United States, and a resident of Cleveland, Cuyahoga county, Ohio, have 5 invented a new and useful Pivot-Pin Support for Couplers, of which the following is a full, clear, and exact description, reference being had to the accompanying drawings, forming part of this specification, in 10 which—

Figure 1 is a vertical section of the lower lug of a car coupler of the Master Car Builders' type showing the supporting stirrup; Fig. 2 is a side elevation thereof; Fig. 3 is a 15 bottom plan view showing the stirrup in section; Fig. 4 is a front elevation of the stirrup before it has been closed on the coupler head; Fig. 5 is a view similar to Fig. 1, showing a modification; Fig. 6 shows the 20 stirrup adapted for use with the device of Fig. 5; Fig. 7 is a vertical section; and Fig. 8 a bottom plan view of a modification; and Fig. 9 is a vertical section on the line 25 IX—IX of Fig. 8.

My invention provides efficient means whereby the broken part of the pivot pin of a coupler can be upheld from dropping from its pivot-hole in case it should break. It is an important safety device, for if a 30 broken pin can be retained with security it will continue to serve as a pivot for the knuckle. It is essential to the success of such support that it should be reliable and should not itself be apt to be broken or displaced, and these qualities are present in a 35 high degree in my device which although movable on the coupler head into and out of supporting position, is nevertheless secured to the coupler head in such manner 40 as to be a permanent part thereof.

The invention comprises a pivot-pin support which is permanently mounted at the base of the coupler in such manner that it can be moved into and out of supporting 45 position. It can assume various forms, some of which I show in the drawings and will now describe.

In Fig. 1, 2 is the pivot-pin and 3 is the lower lug of the coupler-head. This lug 50 terminates in a bottom extension which is preferably constituted by opposite vertical lugs 4 separated by intermediate spaces 5 through which a cotter pin can be inserted into the hole 6 at the end of the pivot-pin, 55 the pivot-pin being inserted from above and

preferably having the usual pin head. 7 is the supporting stirrup which is preferably made of malleable material such as malleable cast iron or pressed steel or cast steel, and is preferably of general U-form having studs 60 8. The stirrup is set in place by bending its ends inwardly so that the studs will enter opposite holes in the lugs 4. The body of the stirrup will then extend beneath the pivot-pin and will tend to remain in that 65 position by reason of its gravity and to resume that position when displaced therefrom, but if it is desired to move it for the purpose of taking out a broken pivot-pin from below or forcing the pin upward, the 70 stirrup can be swung to one side as shown by dotted lines in Fig. 2, and is not restrained from such motion by the pivot-pin. This is advantageous, for it affords ready 75 access to the bottom of the pivot-pin for removal thereof when broken. The easy movability of the device enables the trainmen to ascertain whether the pin is whole. This device is also desirable, because it presents no obstruction to the driving of a drifting 80 tool through the pin-hole. The stirrup remains a permanent fixture on the coupler-head and is not apt to be broken or dislodged. My invention has a further advantage that it enables the coupler to be 85 used either with a pivot pin inserted from below or one which is inserted from above. When it is inserted from below the stirrup is not used but can be replaced by a bolt, the construction of the coupler-head for my 90 device permitting this to be done.

In the modification shown in Figs. 5 and 6, the stirrup has its studs 8' on the outside and it is therefore inserted between the lugs 4 and is bent outwardly so as to push the 95 studs into the holes of the lugs. In this case the lugs should be spaced farther apart than in Fig. 1.

In the modification shown in Figs. 7, 8 and 9, the stirrup 7' is not of U-shape, but 100 has a single stud or pintle 8" journaled in a hole in a vertical lug 4' of the coupler-head, and the body and base of the stirrup extend in L form downwardly therefrom and the base projects under the end of the 105 pivot-pin. The stud 8" is held in its pivot hole by a cotter 9.

I claim:

A car coupler pivot-pin retainer comprising a stirrup having a horizontal bar and a 110

vertical bar, a stud extending from said vertical bar on which the stirrup is adapted to turn, a downwardly extending lug on the bottom of the coupler adjacent to the pivot 5 pin hole through said coupler and having an orifice therethrough for the reception of said stud, the horizontal bar of the stirrup being normally held by gravity across the lower end of the pivot hole to retain the pivot 10 pin within the coupler, said stirrup being

without function in the normal condition of the parts and being movable to one side against the action of gravity for the removal of the pin; substantially as described.

In testimony whereof, I have hereunto set 15 my hand.

HENRY F. POPE.
